APPARATUS FOR REFRIGERATION

Application filed September 12, 1927. Serial No. 219,028.

This invention relates to refrigerating systems and more particularly to refrigerators of that class using a liquefied gas, such as anhydrous ammonia, or any other pre-cooled liquid, as the refrigerant; it being the principal object of the present invention to provide a practical and economical refrigerating system, especially for mercantile establishments and private home use, but suitable also for other uses, which employs no pumps, compressors, motors, or the like, in its operation and which automatically maintains a certain predetermined temperature within the refrigerated area.

More specifically, the object of the present invention resides in the provision of a refrigerating system using a volatile, liquid refrigerant, as above stated, which may be maintained indefinitely in its liquefied state by proper insulation of its container, with an expansion coil located in the area to be refrigerated, and so connected with the container as to be supplied with the refrigerant by gravity flow and only in accordance with the absorption of heat from the refrigerated area so as to thereby automatically maintain a predetermined refrigerating temperature.

It is also an object of the invention to provide means whereby the circulation of air within the refrigerated area and about the expansion coils may be regulated as a means of determining the temperature within the refrigerated area and to insure its being evenly cooled.

Another object of the invention resides in the provision of means for retaining the expanded gas.

Other objects of the invention reside in the various details of construction and particularly in the combination of parts, as will hereinafter be described.

In accomplishing the various objects, we have provided the improved details of construction, the preferred forms of which are illustrated in the accompanying drawings, wherein—

Figure 1 is a vertical section taken transversely of a refrigerating system embodied by the present invention.

Figure 2 is a horizontal section taken substantially on the line 2—2 in Figure 1.

Referring more in detail to the several views of the drawings—

1 designates, in its entirety, the refrigerator body, or housing, which may be of a type and size convenient for mercantile or for household use, or may be made in larger sizes for railway car or other commercial purposes. In its preferred form for domestic use, it would be of box-like form with its walls well insulated in the well-known, or any other suitable manner, so that its inside temperatures would be unaffected by temperatures outside. Within the top of the refrigerator there is provided a compartment 2 within which a tank 3, or receptacle, containing the refrigerant 4, is located. Access to this compartment may be had through a top opening 5 in the refrigerator within which a cover, or wall section, 6, is tightly and removably fitted, and access to the tank is provided for through a top opening within which a plug 3^a is threaded.

Below the compartment 2, and separated therefrom by an insulating wall 7, is the refrigerating chamber 8 and located within the top of this chamber is a series of expansion, or cooling, coils 9 consisting of relatively small pipes which, at their upper ends, connect with a feed pipe 10 leading downwardly through an opening 7' in the partition wall 7 from the base of the tank 3 so that the liquid refrigerant may flow by gravity from the tank into the coils. Preferably, these coils are arranged so as to enclose a rectangular area, as shown in Figure 2, within which a frame structure 12 is supported for containing a plurality of trays 13 which may be slid into and from the same and within which water, or articles of food, may be placed for quick freezing.

This freezing zone 8' is enclosed by a sheet metal housing 14 which is for the purpose of preventing the air within the refrigerating chamber from coming into direct contact with the expansion coils with a resultant lowering of the temperature to a point far below that required or desired; also, for preventing excessive deposit of moisture in the form of 100

frost on the coils which would ultimately insulate them to a certain extent and also to prevent vapors, or odors, from food or articles in the refrigerating chamber 8' from being absorbed by food products being prepared in the trays 13. The walls of the housing 14 are placed close to the coils 9 and this leaves a substantial space between them and the side and top walls of the refrigerating chamber for the circulation of air.

As a means of controlling the circulation of air within the refrigerating chamber as a means of temperature control and also to effect an even temperature throughout the chamber, we have fixed a perforated, sheet metal plate 15 in horizontal position and slightly spaced below the bottom wall 14' of the housing 14 to provide an air circulating space 16 between the two. The side edges 20 of the plate 15 terminate short of the side walls of the refrigerating chamber and these edges are adapted to be bent downwardly, as at 15' in Figure 1, so as to provide air passages 17 of widths or areas which, by experiment, are found to be correct for maintaining a certain predetermined temperature within the cooling area in the lower portion of the refrigerator; this degree of temperature of course being dependent on the temperature 30 made possible by the expansion coils and the rate of air circulation about the expansion coils as determined by the area of the passages 17. Also, extending upwardly from the side edges of the plate 15 in parallel relation to the 35 side and top walls of the refrigerating chamber and also spaced therefrom and from the side and top walls of the housing 14, are plates, or deflectors, 20, which terminate in spaced relation at the top of the chamber. These walls provide that air circulating upwardly within the refrigerating chamber 40 will, after passing through the passages 17, continue upwardly along the sides and top of the chamber walls and will then return downwardly over the top and side walls of the 45 housing 14 and will be cooled by contact therewith and then distributed through the perforations of the plate 15 downwardly into the chamber, as indicated by the arrows in Figure 1. This arrangement of baffle plates 50 retards the air circulation to that extent necessary for insuring a desired temperature within the refrigerating chamber and also effects an even distribution of the cooled air to all 55 parts of the chamber.

It will be mentioned here that access to the refrigerating chamber may be had through an opening 21 at the front of the refrigerator 60 within which a door 22 is fitted, as indicated in Figure 2, and that suitable shelves, as at 23, may be provided in the chamber; however, the details of construction of the housing itself and arrangement and number of doors 65 used is not material to this invention so long

as the housing is well insulated and suitable for the purpose intended.

Connected with the lower ends of the several sections of the expansion coils, is a pipe 25 which extends laterally therefrom above the plate 15 and then turns upwardly through the top of the refrigerator housing and is there provided with a valve 26 and a fitting 27 whereby connection may be made with a device for filling the tank 3 with the refrigerant. 70 Adjacent its point of connection with the coil, this pipe has a "goose neck" fitting 29 which serves as a trap for preventing the refrigerant from flowing into the filling pipe and wasting; it being apparent that gas confined in 80 the upper portion of the pipe 25 will cause the liquid refrigerant to be backed up and retained back of the trap. Leading from the top of the tank 3 is a pipe 30 through which expanded gas may escape from tank 3 and be 85 directed into a retaining tank 31, presently described in detail.

Assuming the device to be so constructed, its operation would be as follows:

First, the tank 3 is filled to a suitable depth 90 with a liquefied gas, such as anhydrous ammonia, or any other suitable pre-cooled liquid; this being admitted to the tank through pipe 25, the expansion coils 9 and 10. Except at times when the tank is being charged, the valve 26 is tightly closed in order to prevent pressure within the tank from forcing the liquid out through pipe 25. Air within the housing 14, or freezing zone 8', is excessively cooled due to its intimate relation with the coils 9. Air circulating within the refrigerating chamber 8 comes into contact with the walls of housing 14 which encloses the expansion coils 9 and freezing zone 8' and heat is extracted from this air by reason of the lower 100 temperature within the housing.

Heat thus transmitted from the air to the coils transforms some of the volatile refrigerant into gas which bubbles up through the pipe 10 into tank 3 and passes off through pipe 30 into tank 31. The rate of this transformation of the refrigerant from liquid to gas is, of course, controlled by the amount of heat that can be extracted from the air and is dependent to a great extent on the rate 110 of circulation of air in contact with the housing 14. In the present instance, the rate of circulation and resultant temperature is controlled by a proper determination of the area 115 of the passages 17. It is readily understood that heat will be extracted from any article placed within the refrigerating chamber for cooling, and this heat carried by the air is ultimately taken up by the coils 9 and absorbed in the gasifying of some of the refrigerant; the rate of which is in proportion to the amount of heat absorbed. It is further understood that, considering the tank 3 to be perfectly insulated, the refrigerant therein 120 will remain in its liquefied state indefinitely 130

and it will be supplied to the expansion coils only as required to replace that given up in the form of gas due to absorption of heat. It is apparent then, that the delivery of refrigerant to the coils is automatically controlled and is more, or less, in proportion to the amount of heat absorbed by the coils from objects placed for cooling within the refrigerating chamber. If no heat can be extracted, no refrigerant is used.

For the purpose of retaining the gas given off from the container through pipe 30, we have provided the tank 31 which is partially filled with water or other absorbent. The pipe 30 opens within the tank close to its base so that the gas from the pipe is caused to bubble into the absorbent which retains it.

In the present illustration, a branch pipe 35 connects with the pipe 30 above the tank 31 and this leads through a 3-way valve 36 into a pipe 37 which opens into the top of the tank. Normally the valve 36 is adjusted so as to close passage through pipe 35 and to connect pipe 37 with atmosphere.

When it is desired to empty the tank 31 of its contents, the valve 36 is adjusted so as to provide direct connection from pipe 30 to the top of the tank. Then the gas becomes confined under pressure in tank 3 and is released into the upper portion of tank 31 and is utilized to expel the liquid from tank 31 through a discharge pipe 42 which leads upwardly from near the base of the tank and through the top thereof. This latter pipe is provided with a water level gauge 43 by means of which internal water level may be determined, and also is equipped with a valve 44 and a connection 45 to which a conduit, not shown, may be attached for filling or emptying the tank.

While we have described this system as arranged for domestic use, it is to be understood that the same system can readily be adapted to commercial purposes, such as in railway cars, ships, refrigerating and cold storage plants, and we do not wish to confine its scope only to the system shown.

Having thus described our invention, what we claim as new therein and desire to secure by Letters Patent, is:

1. A device of the character described comprising an insulated housing providing an insulated compartment in the top portion thereof and a refrigerating chamber below said compartment, an insulated tank disposed within the top compartment for containing a supply of liquid refrigerant, a vent pipe leading from the top of said tank, an expansion coil located within the top of the refrigerating chamber having a pipe connection with the base of the refrigerant container through which the coil may be supplied by gravity flow and through which gas may be vented from the coils, a filling pipe connected with the base of the coil and ex-

tended upwardly to a point above the refrigerant container and a trap in said filling pipe adjacent its connection with the coil for preventing outward passage of the refrigerant.

2. A refrigerator of the character described comprising a housing providing an insulated compartment in the top portion thereof and a refrigerating chamber below said compartment, a closed container disposed within the top compartment for confining a volatile liquid refrigerant, said container having a vent pipe leading from the top thereof, an expansion coil located within the top of the refrigerating chamber having a pipe connection at its top end with the base of the refrigerant container through which the coil may be supplied by gravity flow and through which gas may be vented from the coils, a filling pipe connected with the lower end of said coil having a trap therein adjacent its connection with the coil for preventing outflow of refrigerant, a housing enclosing the coil in spaced relation from the walls of the refrigerating chamber providing an interior freezing zone and air deflecting plates suitably disposed within the refrigerating chamber about the housing for directing the circulation of air.

3. In a refrigerating device of the character described, the combination with an insulated container for a liquid refrigerant having a vent pipe connection at the top and an expansion coil having a pipe connection with the container through which the coil may be supplied with refrigerant by gravity flow and through which gas is vented from the coils into the container, of a closed tank for a gas absorbing liquid, a gas discharge pipe leading from the vent pipe connection of the refrigerant container into the said tank to a point below the liquid level therein, a pipe connection between the said gas discharge pipe and the top of the tank, a valve in said pipe connection whereby direct communication may be made between the gas discharge pipe and the top of the tank, or with atmosphere, and a liquid discharge pipe leading from near the base of the tank through which the liquid may be forced by a pressure of gas delivered from the gas discharge pipe into the top of the tank.

Signed at Seattle, Washington, this 1st day of September, 1927.
